Thomas Tracy.

UNITED STATES PATENT OFFICE.

THOMAS TRACY, OF WASHINGTON, DISTRICT OF COLUMBIA, ASSIGNOR OF ONE-HALF TO THEODORE P. ENGLE, OF VANSVILLE DISTRICT, MARYLAND.

FAUCET AND VENTILATOR FOR BEER, &c.

SPECIFICATION forming part of Letters Patent No. 250,017, dated November 22, 1881.

Application filed June 27, 1881. (No model.)

To all whom it may concern:

Be it known that I, THOMAS TRACY, a citizen of the United States, residing in Washington, in the county of Washington and District 5 of Columbia, have invented a new and valuable Improvement in Faucets and Ventilators for Beer and the like; and I do hereby declare the following to be a full, clear, and exact description of the construction and operation of 10 the same, reference being had to the accompanying drawings, making a part of this specification, and to the letters and figures of reference marked thereon.

My invention relates to improvements in 15 faucets and ventilators for beer and the like; and the novelty consists in the construction and arrangement of parts, as will be herein-after more fully set forth, and particularly pointed out in the claims.

20 In the annexed drawings, Figure 1 is a representation of a longitudinal section of my device, showing the same applied to a part of a barrel. Fig. 2 is a perspective view of the faucet with the ventilating-tube and plunger removed. Fig. 3 is a view of the plunger. Fig. 4 is a sectional view of the plunger, showing the wheel attached. Fig. 5 is a sectional view taken through lines $x-x$ of Fig. 1; and Fig. 6 is an enlarged sectional detail view of 25 the ventilating-tube.

The letter A represents the barrel of the faucet, B the plunger, and C the ventilating-tube. The faucet A has at its outer end a stuffing-box, a, and its inner end is externally 30 screw-threaded, as shown at b, to be screwed into the threaded bushing v in the barrel, as shown in Fig. 1 of the drawings. This faucet is internally screw-threaded, as shown at c, to receive the threaded plunger B in tapping. 35 This plunger B is longitudinally channeled 40 from the point d to d' and thinned down from the latter point to or near the wheel or handle E. The channels f in the plunger are for the passage of liquid from the barrel. The upper 45 channel, g, is for the passage of the ventilating-tube in the keg.

D represents a screw-threaded nozzle, which is cast with the said faucet, and to which the spigot E' may be attached.

F represents a raised portion, which is also 50 cast with the faucet, and is provided with a hole, e, for the passage of the air or ventilating tube. Upon the top and near the end g' of this raised portion F is a transverse slot, f', for the reception of the gate h and the elastic 55 or other suitable packing, h', which serves to form a tight frictional connection with the said gate h.

m' is a transverse groove in the faucet, below the said hole e, to receive the lower edge 60 of the gate h, when the air or vent tube is withdrawn from the hole e of the faucet and the said gate pressed down. This rubber or packing h' is perforated, and surrounds the air or vent tube when the same is inserted through 65 the hole e of the faucet. This air-tube C has inside, near its upper end, a stop, s, for the spiral spring i, which spring is placed between the said stop and cylinder j, the object of which will be hereinafter more fully set forth. 70

Fastened to one end of the cylinder j, as shown in detail, Fig. 6 of the drawings, is a wire or rod, o. This wire or rod passes from the said cylinder down through the vent-tube, and has secured near its outer end a valve or 75 plug, o', and to the extreme outer end of this wire is attached a chain, k, the opposite end of which is attached to the key G' of the spigot.

The operation is as follows: The ventilating-tube C is first withdrawn from the faucet 80 and the gate h pushed down in the groove m'. The end of the faucet is then screwed into the bush in the head of the barrel until there is a tight joint formed between the flange n of the faucet and the head of the bush. The operator then grasps the wheel E of the plunger and screws up the same until the plug is driven in the barrel, when the liquor is ready to be drawn out. When it is necessary to ventilate 85 the barrel for the draft of the liquid contained therein, the end R of the tube C is inserted in the hole e of the faucet until the said end of the tube strikes the gate h. The gate is then raised, and the ventilating-tube, being curved, as shown, is pushed in from the said hole e of 90 the faucet through the channel g of the plunger B and the bush v, and the end R extended above the liquid in the barrel. The packing 95

h' will prevent the escape of any of the liquid out through the hole *e* or the tube-channel *g* and the transverse slot *f'* of the faucet. When the key *G'* is turned to effect an opening at 5 the spigot a simultaneous opening is effected at the outer and inner end of the vent-tube *C* by the chain being tightened, and the valve or plug *o'* thereby being pulled outward. The air thus admitted is allowed to pass into the 10 barrel by the wire *o* connected with the chain pulling down the cylinder *j*, thus causing the apertures *u* of the cylinder to register with the apertures *u'* of the ventilating-tube.

When desired, the ventilating-tube may be 15 withdrawn from the faucet and the gate pressed down, as before described, the chain *k* detached from the key of the spigot, and the faucet used independent of the said ventilating attachment.

A strainer may be attached to the inner 20 screw-threaded end of the plunger, if found desirable.

Having thus described my invention, what I

claim as new, and desire to secure by Letters Patent, is—

1. The faucet *A*, constructed as described, 25 with the enlarged portion *F*, having slot *f'*, to receive the packing *h'* and gate *h*, and the hole *e*, to receive the ventilating-tube, in combination with the plunger *B*, all substantially as and for the purposes specified. 30

2. In a ventilator for beer, the tube *C*, having apertures *u'* and stop *s*, the cylinder *j*, having apertures *u*, the spring *i*, and rod *o*, carrying valve *o'* and chain *k*, secured at one end to the key of the spigot and at its opposite end 35 to the rod *o*, all adapted to operate substantially as and for the purpose specified.

In testimony that I claim the above I have hereunto subscribed my name in the presence of two witnesses.

THOMAS TRACY.
